United States Patent Office

Des. 197,643
Patented Mar. 10, 1964

197,643

CHAIR

Gideon A. Kramer, 2401 SW. 172nd, Seattle, Wash.

Filed Aug. 31, 1962, Ser. No. 71,507

Term of patent 14 years

(Cl. D15—1)

FIG. 1

FIG. 2

FIG 3

FIG 4

FIGURE 1 is a front perspective view of a chair embodying my new design;

FIGURE 2 is a rear elevational view of the chair shown in FIGURE 1;

FIGURE 3 is a side elevational view of the chair shown in FIGURE 1; and

FIGURE 4 is a front elevational view of the chair shown in FIGURE 1.

The design is characterized by the particular one-piece molded seat unit in association with the specifically configured pedestal-leg arrangement, all as shown.

I claim:

The ornamental design for a chair, as shown.
